UNITED STATES PATENT OFFICE

2,438,654

AUTO PARTS WASHER

Victor N. Albertson, Minneapolis, Minn.

Application February 25, 1944, Serial No. 523,828

3 Claims. (Cl. 134—111)

1

My present invention relates to improvements in washing machines for use in washing greasy and dirty machine parts and the like.

More specifically stated, the present invention relates to improvements in washing machines used for the same general purpose as that disclosed in my co-pending application, S. N. 392,267, filed May 7, 1941, under title "Auto parts washer," which matured into Patent No. 2,397,718 on April 2, 1946. Machines made in accordance with the teachings of my prior patent have and are filling an urgent demand for semi-portable machines of the kind described for use in washing machine parts in factories and well-equipped garages and service stations where power for operation thereof is readily available at all the different locations in which the machine is used. However, experience gained in the commercializing of the said machine of my said prior application has shown clearly that there is a further demand for a still more compact, lighter, more readily portable machine capable of accomplishing substantially the same functions as do machines built in accordance with the teachings of my said prior application, but which may be operated completely independent of electrical or other power sources.

The above and numerous other important objects and advantages of the present invention will be made apparent from the specification, claims and appended drawings.

In the accompanying drawings, like characters indicate like parts throughout the several views.

Referring to the drawings:

Fig. 1 is a perspective view of a commercial embodiment of the present invention; Fig. 2 is a transverse vertical sectional view taken on line 2—2 of Fig. 1 and on an enlarged scale; Fig. 3 is a horizontal sectional view taken on line 3—3 of Fig. 2; Fig. 4 is a horizontal sectional view taken on line 4—4 of Fig. 2; Fig. 5 is a detailed sectional view on a still further enlarged scale and taken on the line 5—5 of Fig. 2, some parts on the section line being broken away; Fig. 6 is a view taken on line 6—6 of Fig. 5; and Fig. 7 is a similarly enlarged fragmentary detailed view taken on line 7—7 of Fig. 4.

The preferred embodiment of the invention herein illustrated comprises a fluid container or reservoir 8, and a work table or deck 9. Preferably, and as illustrated, the fluid container or reservoir 8 is cylindrical, with its axis extending vertically, and the work table or deck 9 is rectangular and of considerably greater area than

2

the cross section of the container 8. The top of the fluid containing reservoir 8 is primarily open and is provided, adjacent its upper edge, with an expanded portion 10. One end of the work deck 9 overlies and is supported by the upper end of the fluid reservoir 8, and is provided with an opening immediately overlying the primarily open top of the fluid container or reservoir 8, and immediately surrounding said opening with a depending annular flange 11 that seats in the expanded portion 10 of the fluid container or reservoir 8. At its other or projected end the work deck or table 9 is provided with supporting legs 12. The large opening in the work deck 9 and which is defined by the depending annular anchoring flange 11 is normally largely closed by a removable cover plate 13 having a depending marginal flange 14 that fits telescopically within the depending flange 11 of the deck 9. The flange 14 of the cover plate 13 preferably, and as illustrated, is provided with circumferentially spaced series of drain apertures 15 in the upper portion of its flange 14, and by reference particularly to Fig. 2 it will be seen that the flange 14 has sufficient depth below the apertures 15 thereof to insure the location of the apertures 15 above the surface of that portion of the work deck 9 surrounding the cover plate 13. Cover plate 13 does, of course, complete the bottom of the work deck, which work deck is preferably imperforate except for the fluid return apertures 15.

Preferably means is incorporated in the machine for separating dirt from the cleaning fluid 35 before it is returned to the fluid containing reservoir 8, and a preferred arrangement for accomplishing this result is shown particularly in Fig. 2. By reference to Fig. 2 it will be seen that a circular tray 16, having an outside diameter approximating that of the inside of the reservoir 8 and which is provided at its upper edge with an out-turned seating flange 17, is telescopically seated in the upper end of the reservoir 8 with its said out-turned flange 17 resting on 40 the bottom of the expanded portion 10 of said reservoir. In fact, in the preferred arrangement illustrated, the flange 17 of the tray 16 establishes a stop for the bottom of the flange 14 to cover plate 13. In the construction illustrated, the cover plate 13 and tray 16 are removable at will, but it will be readily seen that with the parts assembled fluid leaking through the circumferentially spaced drain passages or apertures 15 will flow into the outer edge portion of

the tray 16. Incidentally, it should be noted that the work table or deck 9 is provided at its margin with connected upstanding flanges 9' and is, therefore, in the nature of a rectangular tray.

The radially outer portion of tray 16 is preferably imperforate whereas the central portion of the tray is provided with relatively closely spaced drain apertures or passages 18. Surrounding the perforate inner portion of the bottom of the tray 16, but nevertheless spaced radially inwardly of the upstanding sides thereof, is an upstanding annular flange 19 that provides, with the bottom and sides of said tray 16, an annular sediment chamber 20. This flange 19 is welded or otherwise rigidly secured to the bottom of tray 16 to provide a liquid-tight joint therebetween in the bottom of the tray, and is imperforate to a level considerably above the bottom of tray 16, so as to establish a fluid level approximately as indicated in Fig. 2. Preferably, however, the flange 19 extends to a level considerably above the fluid level indicated and is rather closely perforated above said level. The perforations in the upper portion of flange 19 are shown in Fig. 2 and are indicated by 21. In accordance with the preferred embodiment of the invention, herein illustrated, the space within the flange 19 is filled with filtering material 22, such as metal wool, crinkled wire, horse hair, vegetable fibre or the like, and, for the dual purpose of rendering the annular sediment chamber 20 easy to clean and keeping the filtering material 22 in position, the said flange 19 is made inwardly converging or more or less conical.

For delivering cleaning fluid from the tank or reservoir 8 onto the surface of the work deck or table 9 there is provided a delivery pipe or conduit 23 that opens into the bottom portion of said reservoir 8 through a port 24. This delivery conduit 23 is comprised of a rigid vertical lower section and a flexible goose neck like upper portion 23' having a downwardly directed nozzle 25. In the arrangement illustrated, the rigid pipe section of the delivery conduit 23 extends through the bottom of the work table or tray 9 and through a sleeve 26 that is welded or otherwise permanently secured to the bottom of the work table or tray 9 to provide a leak-tight joint.

Reservoir 8 normally contains a body of grease-cutting cleaning fluid such as gasoline, kerosene or the like (y), which is circulated through the delivery pipe 23, discharged over parts being cleaned over the deck 9, and then is returned under the action of gravity to the reservoir 8. The preferred mechanism for producing this circulation of cleaning fluid to and from the reservoir 8 comprises a piston 27 having a one-way acting check valve 28 therein, and a yielding piston operating device in the nature of a coil spring 29. The piston 27 works over an axially extended guide post 30 with which it has sliding engagement through the medium of an intricately formed tube-like guide sleeve 31. This guide post 30 is seated at its lower end on the bottom of the reservoir 8 and is maintained in centered position by means of a centering pin 32. This guide post 30 projects into the upper portion of the reservoir and at its upper end is connected to serve as a support for a mechanism anchoring base 33, which base is also anchored to the side of the reservoir 8 by a screw or the like as at 34. At its periphery the piston 27 has closely fit sliding engagement with the cylindrical wall of the reservoir 8 and is provided with an annular packing groove 35 containing a suitable sealing ring

36. Sealing ring 36 may be made of various different materials and be of various different shapes and designs, but for the purpose of the present case it may be assumed that the packing ring 36 is of synthetic rubber. The spring 29 is interposed between the piston 27 and the mechanism supporting shelf or base 33, which latter acts as a fixed base of reaction for said spring.

10 The check valve 28 is of the type which will automatically close as a result of pressure exerted downwardly on the piston 27 and will open whenever downward pressure on the piston is relieved. While such a valve may take several different forms, I have found the gravity actuated disc valve of the type illustrated in Fig. 2 to be entirely satisfactory for the purpose. In accordance with the present example, the valve port in the piston, indicated by 37, is of relatively large diameter and is controlled by a valve disc 38 having an upstanding stem 39 that works through suitable aperture in a detachable guide bracket 40. Opening movements of the valve are limited by engagement of a stop pin 41 with the guide bracket 40 and upward closing movements of the disc valve 38 are limited by engagement of the valve with its cooperating valve seat.

15 For raising the piston 27 against the action of its yielding bias spring 29, I provide spring loading mechanism comprising a chain 42, a sprocket 43 and a sprocket operating crank 44. The shaft portion of crank 44 extends radially through the side of the reservoir above the fluid level and base or shelf 33 and has its extreme inner end 20 journaled in a combination bearing and chain guide bracket 45 mounted on the base 33. At its outer end portion the shaft end of crank 44 is journaled in a bearing 46. The sprocket 43 is pinned or otherwise secured fast on the shaft end of crank 44, and axial movements of the crank and sprocket are limited in one direction by engagement of the sprocket hub with the side of bearing bracket 45, and in the other direction by engagement of a stop collar 47 with bearing 46. In the arrangement illustrated, the sprocket 43 is mounted directly over the guide post 30, which guide post 30 may be assumed to have pin and aperture engagement with the shelf-like base 33 at its top, just as has the said guide post with the bottom of reservoir 8 at its bottom.

25 The chain 42 works over the sprocket 43 and through apertures 48 in the shelf-acting base 33. (See particularly Figs. 2 and 6.) One end of this chain 42 is anchored to the piston bearing sleeve 31 and 49, and the other end thereof hangs loose. Because one end of the chain 42 hangs loose it is desirable to guide the chain to prevent jumping of the sprocket teeth, and for this purpose the bearing and guide bracket 45 is preferably made to closely follow the chain, and in some instances it is also desirable to further guide the chain by use of projecting guide pins 50.

30 While the work table or deck 9 is primarily formed independently of the reservoir 8, these parts are preferably rigidly anchored together to form an integral unit, which can best be accomplished by welding the flange 11 to the expanded portion 10 of the reservoir 8. The tray 16 may also be welded or otherwise rigidly secured to the reservoir 8, but this tray 16 is preferably removable at will for the purpose of cleaning, as is also the cover plate 13, which latter must be removed for the purpose of servicing the tray.

Operation

When an operator desires to wash one or more parts, he will first operate the crank 44 to thereby raise the piston 27 against the yielding action of the spring 29 from its lower full line position to its upper dotted line position of Fig. 2. Under this upward pull on the piston 27 the valve 28, which is open in a static condition with the piston, will remain open and permit the fluid to be transferred therethrough from the top side of the piston to the lower side. When the piston reaches the top of its upward stroke, and is relieved of lifting pressure, spring 29, being now compressed, will exert a downward biasing pressure on the piston which will immediately produce a closing of the valve 28 and will place the fluid (y) below the piston under sufficient pressure to raise the fluid through the delivery pipe 23 and cause a continuous discharge thereof through the nozzle 25 over and onto the deck and over any parts placed on the deck or held over the deck under the stream. Of course, the piston will now travel downwardly at a rate determined by the rate of displacement of fluid through the discharge conduit 23. The fluid discharged onto the deck or table 9 will be returned to the reservoir on the upper side of the piston through the cover plate drain passages 15, flange passages 21, filter material 22 and tray passages 18. The heavier particles of foreign substance removed from the washed parts over the deck will be deposited in the annular sediment chamber 20 of the tray, and lighter foreign particles will be caught and trapped in the filter material 22, so that the fluid returned to the reservoir will be clean.

In the commercial form of the device illustrated the downward operating cycle of the piston 27 will consume several minutes, during which a steady, uninterrupted flow of cleaning fluid will be discharged through the nozzle 25 for cleaning purposes, and in practice it is found that such an operative cycle is sufficient for most relatively small cleaning operations, but, of course, if the cleaning operation is of extensive nature, the machine may be re-cycled one or more times.

Of course, it will be necessary at intervals to clean the sediment out of the annular chamber 20, and to clean or replace the filter material 22, which latter may be common cotton waste, such as is usually plentiful around machine and repair shops.

What I claim is:

1. In a parts washer of the kind described, a vertically disposed cylinder acting fluid reser-

voir, a work deck overlying and supported from said reservoir, a piston mounted for limited reciprocating movement in the fluid reservoir and having sliding sealing engagement with the inner surfaces thereof, a fluid delivery conduit leading from the reservoir at a point beyond one limit of movement of the piston and arranged to discharge above the said work deck, fluid return passages from the work deck back to that portion of the reservoir lying on the opposite side of said piston, yielding means biasing the piston to move toward one of its extreme positions, manually operated means for returning the piston to its other extreme position against the action of said yielding means, and a valve controlled port in said piston, said valve being in the nature of a one-way opening check valve permitting free flow of fluid therethrough under return movements of the piston and preventing flow of fluid therethrough under operative movements of the piston responsive to the yielding biasing means.

2. The structure defined in claim 1, in which the said manually operated means comprises a crank, a sprocket operated from the crank, and a chain running over said sprocket and having one end anchored to said piston.

3. In a parts washer, a fluid reservoir, a work deck extending over and largely closing the top of said reservoir, a substantially annular sediment chamber located within the reservoir immediately below the overlying portion of said work deck, circumferentially spaced fluid return passages leading through said deck and discharging into said substantially annular sediment chamber, fluid passages through the radially inner wall of the sediment chamber, filter material within the space defined by the inner wall of the sediment chamber and which space has drainage communication with the reservoir, and fluid circulating mechanism delivering fluid from the reservoir to said deck.
